UNITED STATES PATENT OFFICE.

FREDERIC MERIAN, OF PITTSBURGH, PENNSYLVANIA.

COVER-SHIFTING MECHANISM.

1,141,573.

Specification of Letters Patent. Patented June 1, 1915.

Application filed April 23, 1914. Serial No. 834,022.

To all whom it may concern:

Be it known that I, FREDERIC MERIAN, a citizen of the Republic of Switzerland, residing at Pittsburgh, in the county of Allegheny and State of Pennsylvania, have invented certain new and useful Improvements in Cover-Shifting Mechanism, of which the following is a specification.

My invention consists of an improvement in mechanism for manipulating the cover of a soaking pit or other similar furnace, and has for its object to provide means for removing and replacing the cover, and for shifting it laterally from or to its operative position.

One of the objects in view is to provide means for such purpose capable for effecting initial vertical raising of the cover, preferably before the lateral shifting is started, or for final vertical lowering of the cover, preferably after it is laterally shifted back to position, in combination with laterally shifting mechanism in order to prevent friction of the cover on its seat, and to provide means to make the speed of the raising and lowering movement considerably smaller than the speed of the shifting movement.

Preferred embodiments of the invention are illustrated in the accompanying drawings, in which—

Figure 1 is a plan view of the apparatus. Fig. 2 is a longitudinal sectional view on the line II.II. of Fig. 1. Fig. 3 is a cross sectional view on the line III.III. of Fig. 1. Fig. 4 is an enlarged detail view showing the lever-actuating mechanism of Fig. 2 in operative engagement. Fig. 5 is a view in sectional elevation, similar to Fig. 2, showing a modified construction. Fig. 6 is a vertical sectional view through one side of the mechanism, indicated by the line VI.VI. of Fig. 5.

In the drawings, a cover 2 for a soaking pit 3, or other similar furnace, is constructed in any suitable manner of the usual refractory material and metallic reinforcement, and is provided with convenient lifting or supporting means, as transverse strips 4, 4, arched over the cover plate and suitably arranged for effectually supporting its weight. A traveling carriage 5 provided with supported rollers or wheels 6, 6, mounted upon a suitable runway or track 7, is provided with levers 8 for connection with and manipulation of the cover 2.

Levers 8 are pivotally mounted on suit-

able fulcrum supports 9 of the carriage 5, and their short arms are connected by chains or links 10, with the cover, and preferably to the supporting structural members 4 thereof.

The long arm of the lever is provided with a pocket 11, adapted to be located within range of a transverse rod or bar 12, having at its ends rollers 13, 13, and fastened to chains 14, 14, traveling over sprocket wheels 15, 15, and 16, 16, of the driving mechanism. Any other suitable projection on chain 14 may be used for the same purpose.

Sprockets 15 and 16 are mounted upon suitable shafts 17, 18, respectively, the ends of which are carried in suitable bearings 19, 20, one of the shafts, as 18, being actuated in either direction by gearing 21, 22, suitable clutch mechanism 23 being provided for intermittent engagement with a suitable prime mover, as an electric motor, and capable of operation in either direction.

The pocket 11 is formed by oppositely arranged abutments at each side of a central cavity, adapted to receive and engage with the rod 12 in either direction. As shown in Fig. 2, when the cover 2 is lowered, the long arm of lever 8 is elevated, the pocket 11 being then in position to receive and be depressed by the rod 12, at each side, as chains 14 travel in the direction indicated by the arrow. Upon the rod 12 engaging pocket 11, the lever 8 is depressed, the cover 2 being thereby lifted free of its support over the pit 3. The initial part of this operation, it will be observed, will be vertical or very nearly so and will occur before any lateral movement is imparted to the pit cover, if the width of the space between the abutments of the pocket is made slightly in excess of the thickness of rod 12, allowing for lost motion as shown in the drawing. Upon continued movement of rod 12 with chains 14 around sprockets 15 rearward movement will be imparted to lever 8 and carriage 5 thereby, the rod 12 traveling backwardly with the lower strands of the chains, shifting the lever and carriage laterally from the pit 3, and carrying the cover 2 away therefrom in suspended position and clear of the furnace top.

At the same time roller 13 rides under a longitudinal rail 13', thereby retaining the lever 8 in depressed position, with corresponding elevation of the cover. The rear pair of wheels 6 of the carriage,

running upon rails 7, which may conveniently be of channel or other suitable shape, are also provided with upper retaining angles or other suitably shaped rails 24, between which and rails 7 the rollers 6 will travel, preventing any tipping action of the carriage. This stage of the movement is illustrated in Fig. 4, showing the carriage partly moved rearwardly from its normal position of Fig. 2, the rod 12 maintaining its position in the pocket 11. The shifting operation is continued until the cover is shifted backwardly from the pit 3, completely uncovering it, thereupon the rod will 10 then ride out of the pocket 11 at the end of the carriage travel, and ride up around the sprockets 16. The movement of chains 14 may then be reversed, whereupon the rod 12 will then again enter the pocket and thrust 15 against its opposite abutment, shifting the lever 8 and carriage 5 ahead, moving along the lower strands of chains 14 and riding upwardly around sprockets 15, and, after arriving at about the height of the center of 20 the sprockets, will cease to impart any further shifting movement to the cover. At the same time the rod 12 while riding around sprockets 15 will release the lever 8, and 25 complete the lowering of the cover with a final vertical or nearly vertical movement. Pocket 11 may preferably rise slightly higher up with rod 12, so that the final lowering of the cover occurs after the lateral shifting is completed. Rods 12 will then 30 travel away from engagement with pocket 11 around the upper portion of the sprockets and eventually along part of the upper strands of the chains and be stopped there ready for the next operation. By this arrangement it will be seen that the commencement and termination of the traveling movement of the cover does not depend 35 upon accurate stoppage of the chains, but that they automatically engage and disengage with the pocket between proper limits, thereby greatly facilitating the operation. If desired, however, the chains and rod 12 may be stopped at any desired point between the limits of travel of the carriage 40 to effect partial movement of the cover and partial uncovering of the pit. The speed of the raising and lowering movement as compared with the speed of the lateral shifting movement depends on the length of the 45 arms of the lever 8, therefore, the clearance between cover and furnace top can easily be changed or adjusted by changing the length of one or both arms of the lever.

In the modified arrangement shown in 50 Figs. 5 and 6 the carriage 5^a may extend somewhat farther beyond the front wheels 6^a, and is provided with one or more sheaves or rollers 25, over which chains 10^a lead, which are connected with the cover 2 in the 55 same manner as above described. The other

ends of chains 10^a are connected to the short arm of a lever 8^a, pivoted at 9^a upon a suitable bearing upon the carriage, lever 8^a extending into the path of rod 12^b or a roller 12^b thereon, as above described. Pocket 11^a 70 is fixedly mounted on the carriage and in range of the rod 12 or a roller 12^c thereon, when the cover is in normal position. Sprockets 15 revolve on short separate shafts. The construction otherwise is the 75 same as above described.

In operation, roller 12^b rides over the end of lever 8^a, gradually depressing it, lifting the cover 2, and enters between the abutments of pocket 11^a. Thereupon, backward 80 movement is imparted to the carriage, shifting the cover in the same manner, the cover being replaced by reverse movement, and gradually and gently lowered by the receding action of roller 12^b, the completion of 85 the lowering occurring after the carriage has come to rest.

The advantages of the construction will be readily appreciated by all those familiar with this class of mechanism. It is simple 90 and economical in construction, and very effective in accomplishing the several objects in view.

What I claim is:

1. Cover shifting mechanism consisting 95 of a pivoted vertically swinging supporting lever, a rolling support therefor, and independently operable mechanism having a definite range of movement adapted to engage said lever and move it with its rolling 100 support.

2. Cover shifting mechanism consisting of a pivotally mounted vertically swinging supporting lever having a rolling support, a shifting pocket, and an actuating element 105 having a definite range of movement adapted to swing the lever and engage the pocket to shift the lever.

3. Cover shifting mechanism consisting of a pivoted vertically swinging supporting lever, a rolling support therefor, and independently operable mechanism having a definite range of movement adapted to engage said lever and move it with its rolling support and to automatically disengage 110 therefrom.

4. In combination, a rolling carrier, a vertically swinging lever pivoted thereon, a pocket operatively connected with the carrier, and means having a definite range of 115 movement for engaging the lever and pocket adapted to actuate the lever and shift it and its carrier.

5. In combination, a rolling carrier, a vertically swinging lever pivotally mounted 125 thereon and adapted to be connected with a cover or the like, a pocket connected with the carrier, and a chain drive having projections adapted to swing the lever and engage the pocket for raising and shifting the cover. 130

6. In combination, a rolling carrier, a vertically swinging lever pivotally mounted thereon and adapted to be connected with a cover or the like, projections on the carrier, and a chain drive having projections adapted to swing the lever and engage said projections for raising and shifting the cover.

7. In combination, a rolling carrier, a pocket carried thereby, a vertically swinging lever pivotally mounted on the carrier and adapted to be connected with a cover or the like, and an actuating element having a definite range of movement operable to engage the lever and pocket to swing the lever and shift the carrier.

8. In combination, a rolling carrier, a pocket carried thereby, a vertically swinging lever pivotally mounted on the carrier and adapted to be connected with a cover or the like, an actuating element operable to engage the lever and pocket to swing the lever

and shift the carrier, and means controlling the travel of the rolling carrier.

9. In combination, a vertically swinging lever which is supported on a rolling carrier, a shifting pocket connected with said carrier, a chain drive, and projections on said chain drive adapted to swing the lever and shift the carrier by pressing against said lever and against a portion of said pocket.

10. In combination, a rolling carrier, a vertically swinging lever thereon, a shifting abutment operatively connected with the carrier, a chain drive, and a projection on said chain drive adapted to engage and swing the lever and said abutment to shift the carrier.

In testimony whereof I hereunto affix my signature in the presence of two witnesses. 40
FREDERIC MERIAN.
